REFINING HYDROCARBON OILS WITH SULFUR DIOXIDE

John W. Wetzel, Chester, Pa., assignor to Houdry Process Corporation, Wilmington, Del., a corporation of Delaware

Application October 4, 1950, Serial No. 188,283

7 Claims. (Cl. 196—14.11)

The present invention relates to refining and purification of petroleum oils and other normally liquid hydrocarbon materials. An important aspect of the invention is the treatment of liquid hydrocarbon materials, such as whole or reduced crude petroleum oils, shale oils, coal tar oils, etc., or distillate fractions thereof, in the preparation of stocks to be charged to a catalytic conversion operation such as cracking.

By the methods of the present invention there are separated and removed from whole or reduced hydrocarbon crudes or fractions thereof certain deleterious non-hydrocarbon components and contaminants, such as basic nitrogen compounds including such nitrogen compounds which may become converted to deleterious nitrogen bases during further processing or use at elevated temperatures.

These nitrogen compounds when present even in relatively small amounts as of order of 1% or less in hydrocarbon charge stocks subjected to catalytic cracking, act either as transitory "poisons" or deactivants for the catalyst and/or demonstrate an inhibitory effect on the cracking reactions, resulting in reduced yields of desired conversion products, such as gasoline. The presence of these nitrogenous compounds in oil fractions or distillates which are not employed as cracking stocks also may be detrimental for certain uses; for instance in oils to be used as lubricants, fuel oils, medicinal oils, transformer oils, etc.

Liquid sulfur dioxide has heretofore been employed at low temperatures and in substantially anhydrous state in the separation of various hydrocarbon constituents from oils, such as olefinic and aromatic hydrocarbon compounds.

It has now been found that mixtures of sulfur dioxide and water in selected concentration and amount can be employed at ordinary or elevated temperatures for the selective extraction of basic materials from petroleum oils and other liquid hydrocarbon fractions. The presence of water in suitable amount reduces the solubility of aromatic hydrocarbons in the sulfur dioxide under the operating conditions employed so that this material remains substantially entirely in the raffinate.

In accordance with the present invention petroleum oils or other normally liquid hydrocarbon fractions containing basic compounds are treated in liquid state with particular quantities of sulfur dioxide and water, hereinafter specified, at ordinary or elevated temperatures, effecting selective formation of sulfite addition compounds of the bases which are collected in an aqueous acid layer readily separated from the oil raffinate. The acid layer containing the addition salts of the bases is decomposed to regenerate the sulfur dioxide for further use in the process while setting free the bases in a condition such that they are readily separated from the aqueous acid extract.

There is thus obtained by the process of the invention a hydrocarbon fraction of reduced nitrogenous content which may provide an improved material for charging to a catalytic cracking or other catalytic hydrocarbon

conversion operation. From the acid extract available nitrogenous fractions or compounds can be economically recovered by suitable methods of fractionation or by hydrogenolysis, with or without previous separation into fractions, as more particularly described in my copending application Serial No. 128,761 of November 22, 1949 now Patent No. 2,704,758.

In a typical operation in accordance with the invention the oil to be extracted is contacted with a mixture of 10 SO₂ and water containing an amount of SO₂ in excess of the stoichiometric quantity required to form sulfuric acid, at a temperature sufficiently high to reduce the viscosity of the oil, if necessary, and under atmospheric or superatmospheric conditions required to retain the oil 15 in liquid state. The oil and sulfur dioxide-water extractant are thoroughly agitated as by stirring if batch operation is employed, or by countercurrent flow of oil and aqueous acid mixture in a suitable tower, one form of which is hereinafter described. There is thus obtained 20 on subsequent settling, an acid layer containing base sulfites soluble therein and an oil layer readily separable therefrom. By distillation of the acid layer SO₂ is volatilized leaving a still residue of bases and water which are separated by settling. If low molecular weight bases 25 are present to any significant extent, these may be separated from the water layer by salting out.

The proper selection of the proportions of sulfur dioxide to oil and the concentration of sulfur dioxide with respect to the water are of the utmost importance. It 30 has been found that for the desired extraction of nitrogenous bases from oils containing the same without accompanying removal of large quantities of hydrocarbon components of the oil, the sulfur dioxide can be effectively employed in weight ratios of from about 15 to 150% 35 by weight of the oil, and preferably at 30 to 50% by weight of the oil. The quantity of water used should be in excess of that which will dissolve in the oil. With most oils of the type described and under the extraction conditions employed, a quantity of water equal to 40 at least about 0.5% and up to about 5.0% by weight of the oil is to be used. The quantity of water, also, should be less than the stoichiometric quantity required to form sulfuric acid with the SO₂ employed, so that SO₂ is always present in excess. Use of larger quantities of water, 45 as above 5.0% by weight of the oil, necessitates an increased sulfur dioxide content in the extractant to obtain the same extent of extraction of nitrogenous bases.

With increasing ratios of SO₂ to oil more aromatics are dissolved in the extract with the tendency toward the 50 formation of tarry materials interfering with extraction. If insufficient SO₂ is employed, nitrogen bases are not extracted or are extracted to only a minor extent comprising chiefly the strong nitrogen bases which form stable acid sulfites that are not readily hydrolyzable. On the other hand by using the proportions of SO₂ and water within the range set out above, hydrolysis of even the 55 weakest nitrogen base acid sulfite salts is prevented and these weak bases are removed in the extract along with the strongly basic compounds.

Fairly light hydrocarbon oils, such as those having a gravity and viscosity in the range of gasoline and kerosene, may be extracted at room temperature and under atmospheric pressure. With heavier or more viscous oils temperatures should be raised sufficiently to reduce the viscosity of the oil to facilitate admixture with the extractant, the pressure being raised sufficiently to maintain the oil in liquid state. Thus for instance with a light gas oil of about 20 to 25° API gravity, temperatures of 120-150° F. may be employed and pressures from about 50-300 pounds per square inch gauge.

In the accompanying drawings there is shown a flow diagram illustrating a preferred method of carrying out

the extraction in a continuous countercurrent extractor. If desired the extractor may be packed to provide better contacting of the extractants with the oil. It will be understood that in practical operation the inlet lines for SO₂ and sulfurous acid should be provided with diffusers, spray nozzles, etc. to obtain intimate mixing.

After equilibrium is established in the system there will be contained in the tower 1 stratified layers of oil, sulfurous acid and base sulfites. In the operation of the system, the charge stock to be extracted is introduced into the extractor below the interface of the oil-sulfurous acid for initial admixture with the sulfurous acid, the raffinate being removed near the top of the oil layer as indicated at B. Moist sulfur dioxide is introduced directly into the oil as indicated at C and passes upwardly through the oil, unreacted SO₂ being removed above the oil layer at D and recirculated. The SO₂ passing through the oil effects desired agitation of the oil. The moisture content of the SO₂ stream is maintained by introducing steam into the line entering at C. Sulfurous acid and base sulfites separate out from the oil layer and form on settling separate layers with the base sulfites below the sulfurous acid. A portion of the sulfurous acid is continuously withdrawn from that layer, as indicated at E, and returned to the top of the oil layer at F to cascade countercurrently through the oil. Water may be added in the sulfurous acid line to maintain the required water content of the system, or alternatively all of the makeup water may be supplied by the steam admitted to the SO₂ stream.

The raffinate removed at B is relatively free from basic constituents and contains dissolved and entrained sulfur dioxide and sulfurous acid. This raffinate is passed into a degasser 2, maintained at lower pressure than the extractor and at a temperature below the initial boiling point of the oil. From the degasser extracted oil is removed, which is sufficiently free from sulfur dioxide for most practical purposes. Last traces of sulfur dioxide may be removed from the oil by washing with dilute caustic. The SO₂ from the degasser, which may contain a small amount of water is sent to storage vessel 3, to be recycled in the process with the addition of makeup SO₂ as required.

The basic sulfites are removed from the bottom of the extractor G and subjected to flash distillation 4 at temperatures effecting thermal decomposition of the sulfites, obtaining an overhead stream of SO₂ and the free nitrogen bases as a residue. The sulfur dioxide overhead from flash distillation is sent to storage vessel 3 and is recycled.

Instead of thermally decomposing the nitrogen base sulfites, the free bases may be released by hydrolysis, with or without the presence of a small amount of caustic.

In a properly balanced system the amount of water added as steam to the SO₂ line or for dilution of the sulfurous acid from E in that line, or both, will be sufficient to keep the level of the H₂SO₃ layer below the oil fairly constant.

The method above described is particularly attractive because of the facility of separating the oil and the base sulfites, and is economically desirable from the standpoint of low cost operation as a result of good recovery of SO₂ for recycling.

By the methods of the invention not only can there be refined and improved oils required for use as charging stock to catalytic cracking or other catalytic conversion, but also other hydrocarbon fractions such as gasolines, fuel oils, light naphthas, kerosene, or diesel fuels, may be treated to improve color and oxidation stability and render them more resistant to sludge formation and other undesirable side reactions. In addition, heavier oils such as lube oils, transformer oils, etc. can be beneficially improved by the described treatment.

Example

A Los Angeles Basin gas oil boiling in the range

440-950° F. and containing 0.39% by weight N and 1.08% S, was subjected to flash vaporization and the overhead (80%) subjected to extraction with SO₂ and water under the conditions indicated in the following table and with the results therein tabulated:

Wt. Oil, g.	531.8	1,116.2	1,211	1,142
Wt. H ₂ O, g.	10	25	50	50
Wt. SO ₂ , g.	86.9	510.8	1,225	1,840
Wt. percent H ₂ O in Liquid Charge	1.8	2.2	4.0	4.2
10 Wt. percent SO ₂ Based on Oil + H ₂ O	16	45	97	154
Maximum Pressure, p. s. i. g.		125	300	300
Temperature, ° F., approx.	80	125	180	180
Product:				
Wt. percent N in Raffinate	0.26	0.26	0.23	0.20
Wt. percent S in Raffinate			1.05	0.95
15 Percent N Removed	30	30	41	48
Vol. percent Extract			ca. 4	

For oils of lower specific gravity than water and having a low viscosity, as up to about that of kerosene, extraction is readily carried out at room temperature; higher temperatures may be employed, if desired, even for such oils. For more viscous oils and particularly those having a high specific gravity, heating is essential to facilitate good contact between the oil and the sulfur dioxide.

25 Whenever elevated temperatures are employed, the pressure should also be raised to an extent at least sufficient to maintain the oil in liquid state. In the cold, as at temperatures of about and below 0° C., selective extraction of nitrogen bases is not obtained, since the dissolution of aromatics or other hydrocarbons is favored thereby.

30 Obviously many modifications and variations of the invention as hereinbefore set forth may be made without departing from the spirit and scope thereof and therefore only such limitations should be imposed as are indicated in the appended claims.

I claim as my invention:

1. The method of refining hydrocarbon oils boiling above the range of gasoline which comprises extracting such oils in liquid state and at normal to elevated temperatures with a mixture of sulfur dioxide and water, separating the thus formed aqueous acid layer from the oil raffinate, decomposing sulfite addition compounds present in the aqueous acid extract to regenerate sulfur dioxide, and then separating from the extract organic bases set free by such decomposition, the mixture of water and sulfur dioxide employed in said extracting containing water in excess of its solubility in the oil and from 0.5 to 5% by weight of the oil and containing SO₂ in excess of the stoichiometric quantity required to form sulfurous acid with the water present, said mixture being employed in quantities providing 15 to 150% SO₂ by weight of the oil.

2. The method according to claim 1 wherein said mixture is employed in proportions furnishing 30 to 50% SO₂ by weight of the oil.

3. The method of preparing a charge stock for catalytic cracking which comprises removing contaminating nitrogenous bases from a hydrocarbon oil boiling in a range above gasoline, by extraction with a mixture of sulfur dioxide and water at elevated temperature and at a pressure sufficient to maintain the oil in liquid state, the mixture of sulfur dioxide and water containing SO₂ in free and combined state equal to 15 to 150% by weight of the oil and water in excess of its solubility in the oil but not more than 5% by weight of the oil, and separating the thus formed aqueous acid layer from the oil raffinate.

4. The method according to claim 3 wherein said mixture is employed in proportions furnishing 30 to 50% SO₂ by weight of the oil.

5. The method of extracting nitrogenous bases from hydrocarbon oils boiling above the range of gasoline, which comprises passing moist SO₂ upwardly through a body of such an oil while simultaneously passing sul-

furous acid downwardly through said oil, said sulfurous acid forming a layer below said body of oil, and an aqueous layer containing addition compounds of such nitrogenous bases in the form of sulfites being formed below said sulfurous acid layer, continuously admitting oil to be treated at the bottom of said body of oil and removing oil raffinate near the top thereof, removing SO₂ in vapor phase above said body of oil, adding moisture to said SO₂ and recirculating for further upward passage through said body of oil, withdrawing sulfurous acid from said layer thereof and recirculating the same to the top of said body of oil, continuously withdrawing the aqueous layer containing said addition compounds, decomposing said addition compounds to free the nitrogenous bases, separating the freed bases from the aqueous residue, said SO₂ and oil being continuously supplied in the proportions of 15-150% SO₂ by weight of the oil, and said water being maintained at 0.5 to 5% by weight of the oil.

6. The method according to claim 5 wherein the oil and SO₂ are continuously supplied for said extracting in the proportions of 30 to 50% SO₂ by weight of the oil.

7. In the extraction of heated hydrocarbons with a solvent consisting predominantly of liquid SO₂, the method

of repressing the extraction of aromatic and olefinic constituents and enhancing the extraction of nitrogenous materials from the hydrocarbon layer into the SO₂ layer which consists of maintaining in the SO₂ a significant amount of water, less than the stoichiometric quantity required to form sulfurous acid, and less than 5% by weight of the hydrocarbon, but more than 0.5% of the hydrocarbon, said mixture of SO₂ and water being employed in portions furnishing 15-150% SO₂ by weight of the hydrocarbon.
